CLAIM

The ornamental design for a fishing gig, as shown and described.

DESCRIPTION

FIG. 1 is a perspective view of the fishing gig showing our new design;

FIG. 2 is a right end elevational view thereof;

FIG. 3 is a left end elevational view thereof;

FIG. 4 is a front elevational view thereof, the rear elevational view being a mirror image of the view shown in this Figure; and,

FIG. 5 is a top plan view thereof, the bottom plan view being a mirror image of the view shown in this Figure.
